UNITED STATES PATENT OFFICE.

HENRY SCHWAB, OF ARLINGTON, COLORADO.

SHUTTLE.

1,186,445.

Specification of Letters Patent. Patented June 6, 1916.

Application filed February 8, 1916. Serial No. 77,003.

To all whom it may concern:

Be it known that I, HENRY SCHWAB, a citizen of the United States, residing at Arlington, in the county of Kiowa and State of Colorado, have invented new and useful Improvements in Shuttles, of which the following is a specification.

This invention relates to shuttles and more particularly to means for easily threading the same and it consists in the novel features hereinafter described and claimed.

An object of the invention is to provide a device adapted to be applied to the side of a shuttle and which may be used for directing the thread into the recess at the side of a shuttle when the same is threaded and the said means also serves as a retainer for properly holding the thread in the recess while the shuttle is in use.

With this object in view the device consists in providing a member hingedly mounted at the side portion of the shuttle and which is retained by a spring in position over the recess. The end portions of the said member are embedded in a groove provided at the side of the shuttle whereby the end portions of the said retaining member are prevented from catching in material as the shuttle is used for weaving purposes.

In the accompanying drawing:—Figure 1 is a perspective view of the shuttle. Figs. 2, 3, and 4 are detail views of the features thereof.

The shuttle 1 is of the general configuration as commonly employed for weaving cloth or other similar material, and it is provided with a longitudinally disposed opening 2. A stud 3 is positioned at one end of the opening 2 and a bobbin 4 may be mounted upon the said stud in the usual manner. A hook 5 is mounted at the opposite end of the opening 2 from that end at which the stud 3 is located and the thread from the bobbin is adapted to pass through the said hook. The shuttle 1 is provided at its side with a recess 6 and is further provided at the same side edge at which the said recess is located with a groove 7, the said groove being disposed longitudinally of the shuttle and extending down along one side edge thereof. A member 8 is pivotally mounted in the groove 7 and is provided with pointed ends which are normally housed in the end portions of the said groove. The member 8 is provided at its outer portion and at its lower edge with a notch 9 which

is adapted to register with the lower outer portion of the recess 6 provided in the side of the shuttle. The member 8 gradually increases in transverse or vertical thickness 60 from its pointed ends toward its intermediate point and a spring 10 is located in the groove 7 and bears at one end against one end portion of the said member 8 and at its other end against the bottom of the groove 65 and is under tension with a tendency to normally hold the opposite end portions of the member 8 housed in the end portions of the groove 7 whereby the end portions of the said member may not interfere or catch in 70 the material when the shuttle is used for weaving purposes.

In order to thread the shuttle an operator places his finger upon that end portion of the member 8 against which the spring 10 75 bears and depresses the said end of the member 8 against the tension of the spring whereby the opposite end of the member 8 is moved up out of the groove 7. The thread then may be caught under the elevated end 80 of the member 8 and carried down and seated in the lower portion of the recess 6 and in the notch 9. When so positioned the thread is ready to pass out of the shuttle during the weaving operation. 85

From the above description taken in conjunction with the accompanying drawing it will be seen that a simple and durable means for assisting in threading a shuttle is provided and that the said means may be easily 90 and quickly used for properly locating the thread in the shuttle preparatory to using the shuttle for weaving cloth or other fabric.

Having described the invention what is claimed is:—

1. A shuttle provided at its side with a recess and having a groove extending beyond the opposite sides of the recess and along the outer portion of the body of the shuttle, a spring pressed member pivotally mounted in the groove and having pointed ends and provided at a point between its ends with a notch adapted to register with the lower portion of the said recess in the body of the shuttle. 95 100 105

2. A shuttle comprising a body provided at its side with a recess and having a groove extending along its upper edge and along its side at the opposite sides of the said recess, a spring pressed member having pointed 110 ends, the said spring adapted to normally hold the pointed end portions of the said

member housed in the end portions of the groove, said member increasing in transverse thickness from its pointed end portions toward its intermediate portion and provided at its edge at the said thickened portion with a notch adapted to register with the inner end portion of the said recess.

In testimony whereof I affix my signature in presence of two witnesses.

HENRY SCHWAB.
